C. NICOLLE

2,515,378

DISPENSING PACKAGE OF TABLETS AND THE LIKE

Filed Jan. 10, 1946

FIG. 1

FIG. 2

INVENTOR
Charles Nicolle
By

George Sherry

ATTORNEY

rib and said second side wall defining an outlet passage leading to said outlet opening for receiving said single row of articles, said space between the rib and the opposite surface of the other main wall member being sufficient to permit the portions of the main wall members adjacent said outlet passage to be moved toward each other at any point along the passage far enough to engage an article in said single row and retain it and the articles behind it in the package during a dispensing operation.

CHARLES NICOLLE.
